SWINGING DOOR MECHANISM

Ernest L. Shaffer, Vinton, Iowa

Application June 6, 1931, Serial No. 542,672

24 Claims. (Cl. 20—20)

This invention is a novel "overhead" swinging door mechanism particularly adapted for use in garages and the like, in which a plurality of hinged door sections are movable as a unit from "open" to "closed" positions, and vice versa; the door carrying and actuating mechanism being adapted to be installed in the ceiling of the garage. The present application is a continuation-in-part of my co-pending application Serial No. 5 391,445, filed September 9, 1929, and covers certain novel improvements in the apparatus and essential features of the mechanism.

The principal objects of my invention are to provide a unit as above described which will be 15 easy to install and operate; which will be stable, strong, weatherproof, and will not bind during 20 operation thereof; also a unit which will be completely housed within the garage or other enclosure in any and all positions of the doors; and 25 which will require very little space for operation; which will not be affected by any twisting of the frame of the garage or other building; which will not permit the doors to drag upon the floor while swinging; and which will permit one door section 30 to be opened independently of the other sections; also to provide novel electric means for opening and closing the door assembly.

I will explain the invention with reference to the accompanying drawings which illustrate one 35 practical embodiment thereof to enable others to adopt and use the same; and will summarize in the claims the novel features of construction, and novel combinations of parts, for which protection is desired.

In said drawings:—

Fig. 1 is a plan view looking upwardly at the base unit, at the compound lever carrying the door assembly, and at the power operating means for the assembly; the doors being shown in 40 "closed" position in full lines, and in "open" position in dotted lines. Fig. 2 is a view similar to Fig. 1 but showing the parts as they appear in partly "opened" position of the doors. Fig. 3 is an enlarged section on the line 3—3, Fig. 1. Fig. 4 is a rear elevation of the lock for 45 the door assembly. Fig. 5 is a section on the line 5—5, Fig. 3. Fig. 6 is a rear elevation of the door assembly on the line 6—6, Fig. 1. Fig. 7 is an enlarged longitudinal section through the 50 compound lever, base unit, and bracket connections which adjustably support the door assembly. Fig. 8 is an enlarged longitudinal section through the electric assembly operating carriage and track. Fig. 9 is a transverse section through 55 the electric carriage on the line 9—9, Fig. 8.

Fig. 10 is an enlarged detail. Fig. 11 is a top plan view partly in section of the means permitting independent opening of one of the side doors. Fig. 12 is a plan view, similar to Fig. 1, showing a modified form of the single entrance 5 feature. Fig. 13 is an enlarged longitudinal section through the compound lever showing modified connection of the link, for the single entrance door, to the toggle block. Fig. 14 is an enlarged plan view of the connections between 10 the link and toggle block. Fig. 15 is a vertical section through the single entrance door and the latch means for operating the single entrance feature. Fig. 16 is a plan view of the single entrance door. Fig. 17 is a detail perspective of 15 the latch casing.

As shown, my invention consists of a preformed base unit adapted to be secured to the rafters or ceiling R of a garage or the like opposite the door opening S, said base unit carrying a compound 20 lever with brackets vertically adjustably supporting the middle door section B of the hinged door assembly A, B, C, the door sections A and C being hinged respectively to the opposite side edges of the middle section B.

In place of the relatively thick wooden base plate shown in my co-pending application Serial 25 No. 391,445 I prefer to use a fabricated preformed metallic base unit which when installed against the underside of the rafters or ceiling will occupy, with its related or associated parts, only about five or six inches of ceiling depth. Said base unit, while supporting the carriage and counterbalance lever for said door assembly, also 30 controls the swing, during the opening and closing movements, of the end door sections A and C, and for this purpose the edge of plate 1 adjacent opening S has a compound curvature consisting of an arcuate channel portion 1a concentric with the pivot bolt of the compound lever 40 (hereinafter described), the arcuate channel 1a embracing the full width of middle door section B when in fully "closed" position (full lines, Fig. 1) and the full width of the door B when in fully "open" position (dotted lines, Fig. 1) to permit 45 operation of the carriage 2a of middle door section B through an arc of slightly more than 90 degrees.

Radially disposed bars 1b connect the upper leg of the channel 1a with a center bearing 1c (Fig. 50 7) for pivot bolt 2b. Substantially tangent to the ends of the channel portion 1a but spaced therefrom are frame members 1d forming together a right angle having its heel disposed at a point opposite the center of channel 1a, said frames 1d 55

extending beyond the ends of the channel $1a$ a distance corresponding with the position of outer doors in fully opened or closed positions, or with the outer tips of the reverse curve portions $1d$ of the guide plate shown in my co-pending application, Serial No. 391,445.

Secured to each end of arcuate channel $1a$ is a reverse curved guide plate $1e$ adapted to align doors A and C edgewise with door B when in either "open" or "closed" positions, doors A and C being provided with rollers A' and C' respectively adapted to engage the guides $1e$ and being directed thereagainst by means of guide plates $1f$ secured in the bosom of frame $1d$ and disposed substantially parallel with guide plates $1e$ to form channel guideways for the rollers A' and C' . Shield plates $1g$ are applied over the upper edges of the guide plates $1e$, $1f$ and frames $1d$ to give strength to the structure and to promote smooth and unhindered movement of the guide rollers A' , C' throughout their reverse curve travel.

Preferably spring tension adjustments are provided for the outer ends of the guide plates $1e$ so that the outer ends of the guide plates $1e$ may yieldably hold the end doors, when in closed position, tightly against the door jambs, for the purpose of rendering same weatherproof. As shown in Figs. 1 and 2 the spring adjustments consist of threaded rods $1h$ extending from the frame members $1d$ through the guide plates $1e$, with nuts on the outer ends of the rods, and springs $1j$ interposed between the nuts and the backs of plates $1e$. By adjusting the nuts the spring tensions may be varied.

35 The compound lever for supporting the door comprises an inner frame consisting of parallel members 2 connected together at their inner ends by a pivot block $2c$ receiving the pivot bolt $2b$. The outer ends of frame members 2 are connected directly to the carriage $2a$ of middle door B , which carriage $2a$ is provided with rollers $2d$ adapted to traverse the arcuate channel $1a$ of the base unit as the carriage $2a$ is swung around by frame 2 from "open" to "closed" position.

45 Depending from the center of carriage $2c$ is a vertically disposed bracket 3 lying adjacent the rear face of middle door B . The bracket 3 being carried by the carriage $2a$ and frame 2 will rotate therewith in a fixed horizontal plane. Bracket 3 is provided with spaced perforated ears $3a$, $3b$ carrying a vertically disposed hinge rod $3c$. Rod $3c$ also passes through perforated ears $4a$, $4b$ of a bracket 4 fixed upon the rear face of door B whereby door B may readily pivot on said bracket 3 during the opening and closing movement of the door. The ears $4a$, $4b$ of the bracket 4 are embraced by the ears $3a$, $3b$ of bracket 3 (see Fig. 7) and under the lower ear $4b$ is a stirrup 5 for vertically adjusting door B with respect to the carriage $2a$, the upper ends of stirrup 5 being connected with the counterbalanced outer frame 6 of the compound lever.

Bracket 3 is preferably L-shaped with the vertical leg carrying the pivot bolt $3c$. The horizontal leg is provided with an elongated slot $3d$ at its outer end adapted to be engaged by a bolt $2g$ carried by a clip $2r$ on frame 2 whereby the bracket 3 may be moved on the frame 2 towards or away from the door B to adjust the bracket 3 when carrying the doors to suit the door jambs while permitting free opening and closing movement of the doors. The heel end of the bracket 3 is slidably supported by a strap $2s$ on the under side of carriage $2a$. The legs of bracket 3 are 75 preferably braced by a diagonal strut $3f$ connect-

ing the legs; and when adjusted the vertical leg of bracket 3 carrying rod $3c$ is braced laterally by a brace $2v$ depending from the carriage $2a$ and bolted as at $2w$ to the leg of bracket 3 . Brace $2v$ is preferably sufficiently flexible to permit adjustment of bracket $2d$ axially of frame 2 .

In my co-pending application Ser. No. 391,445, the upper rails on the outer faces of doors B and C have to be made arcuate so as to permit the assembly to swing from front to side positions past the door frame S , this being due to the fact that the middle door B in that case was rigidly bracketed to the carriage $2a$ (instead of being pivoted with respect thereto as in the present application) and in starting to open the doors B and C would necessarily swivel so that one corner would project beyond the normal plane of the closed doors. The present arrangement however in which the door B is pivoted with respect to carriage $2a$ has a decided advantage in that it permits the angularity of door B to change with respect to that of the carriage $2c$ or the axis of frame 2 resulting in a flatter sweep in traversing the reverse curved portions of the base unit by the rollers on end doors A and C . Also in the present pivotally connected arrangement the door B has no tendency to initially swivel upon commencement of the opening movement.

The compound lever also includes an outer counterbalancing frame comprising a pair of parallel spaced members 6 suitably connected together and pivoted for vertical movement as at $3a$ to extensions $2p$ of the pivot block $2c$ of the frame 2 whereby frame 6 swings laterally with frame 2 as the latter is swung, and at the same time may pivot vertically with respect to frame 2 . The forward ends of the frame members 6 are pivotally connected to the upper ends of the legs of the stirrup 5 which vertically adjusts the bracket 4 on the back of door B with respect to the fixed bracket 3 carried by carriage $2a$. The rear end of frame 6 extends beyond the pivot block $2c$ and carries a counterbalancing weight $6b$ for offsetting the combined weights of the door sections A , B , C , so that the doors A , B , C may be readily raised and lowered with respect to the garage floor level in order to overcome the undesirable feature of drag which is common to most garage doors, and in order to lift the doors above their respective floor blocks $A2$, $B2$, $C2$ (Figs. 6 and 7) when opening and closing the doors. The position of weight $6b$ may be made adjustable. The pivot $6a$ for frame 3 is preferably disposed considerably in advance of the pivot bolt $2b$ of frame 2 so as to permit use of a counterbalance $6b$ of minimum weight, and the pivot point $6a$ may be made adjustable.

When the door assembly is in "closed" and "locked" position, the doors are held against inward thrust at their lower ends by floor blocks $A2$, $B2$, $C2$ (Figs. 6 and 7) disposed behind each of the doors, but it is necessary as above stated to raise the door assembly above the tops of the said floor blocks $A2$, $B2$, $C2$, in opening and closing the door assembly; and at the rear end of frame 6 is mounted a roller 7 adapted to engage the underside of the ceiling R , the ceiling having an opening R' therein in way of the roller 7 when the doors are closed so as to permit the lower ends of the doors A , B , C , to drop upon the garage floor in front of the floor blocks $A2$, $B2$, $C2$ when the assembly is in "closed" position whereby the lower ends of the doors will be held tightly against the door jambs. When however the frame 6 starts to swing laterally the roller 7 which would be made 75

of sufficient diameter will engage the underside of ceiling R and thereby raise the doors A, B, C, above the floor blocks and holding the assembly thus raised during swinging of the assembly from 5 "closed" position.

In connection with the end doors A and C I provide toggle links 8 respectively pivoted on a toggle block 8a slidably mounted in guide slot 6x carried by the frame 6 in rear of pivot block 2c of frame 2, and the outer ends of the links 8 are respectively connected with the brackets of rollers A' and C', whereby as the door assembly is swung from closed to open positions the links 8 will be moved simultaneously and cause the inward or outward motion of one door A or C to be imparted through the toggle action to the other door C or A. Referring to Fig. 1 it will be seen that the outer end of the reverse curved guide 1e of the base unit is engaged by the roller C' on door C while the roller A' of door A is entirely disengaged. Now as the assembly is swung from "closed" to "open" position (shown in dotted lines in Fig. 1) the roller C' will necessarily follow its related reverse curve channel (between guides 1e, 1f) towards the arcuate channel 1a, and the toggle link 8 of door C will shift toggle block 8a rearwardly on frame 6 causing the door A (through the medium of its toggle link 8) to swing through the substantially same angle as the door 30 C, so that while the door assembly is being swung to "open" position when the roller C' reaches the end of its reverse curve channel (between guides 1e, 1f) the roller A' of door A will have entered into its related reverse curve channel, and door C 35 during the remainder of the "opening" movement of the assembly will be controlled by and with the movement of door A. Hence when fully swung around to "open" position all three doors A, B, C, will again be aligned along the side wall 40 of the garage as shown in dotted lines in Fig. 1.

I provide a spring 8s connecting the toggle block 8a with the outer end of the horizontal leg of bracket 3 (or with any other fixed part of the compound lever) for tending to hold the doors 45 A, C, fully extended into the plane of middle door B, and thereby yieldably maintaining a "flattening" effect of the door assembly throughout the entire opening and closing movements.

I also provide means whereby one of the end 50 door sections may be opened independently of the other doors for use as a single entrance. If one of the side doors such as C is to be used as a single entrance door, its floor block A2 would necessarily be hinged or yieldably mounted. As described in 55 my co-pending application Ser. No. 391,445 said means preferably comprises a bar 9 (Figs. 1 and 11) adapted to normally overlie the top of door C, the inner end of bar 9 being pivotally secured as at 9a to the top of door B. The outer end of bar 60 6a carries an enlargement 9b upon which the guide roller C' of door C is journaled, and the toggle link 8 of door C is pivoted as at 9c to portion 9b. The enlargement 9b of bar 9 is also provided with an arcuate portion 9d adapted to slidably engage the top of door C to support the outer 65 enlarged end of bar 9 carrying roller C' when door C is opened as indicated in dotted lines, Fig. 11, regardless of the position of door C. Hence the position of roller C' will remain at all 70 times the same as though the roller C' were actually carried by door C with no provision for independently opening door C. A notch 9e formed in plate 9b is adapted to receive a latch 9f (Fig. 6) operated by a knob 9g placed at usual height on 75 door C said knob being connected by a link 9h to

bell crank 9k the vertical arm of which extends upwardly and forms the latch 9j which engages notch 9e. A spring 9m normally maintains latch 9f engaged with its notch. Door C may thus be freely opened and closed without affecting the 5 position of its roller C'; and door C may be locked in normal position by latch 9f engaging notch 9e.

A modification of the single entrance feature is shown in Figs. 12-17 inclusive in which the toggle link 8 for the door A is connected as in Fig. 1 10 to the toggle bolt 8a, but the bracket C' for door C is identical with the bracket A' of door A, and toggle link 8 of door C extends beyond the toggle bolt 8a, and passes through a guide 8g pivotally mounted on toggle bolt 8a (Fig. 13). Guide 8g 15 preferably comprises a metallic plate having a perforation at its center for engagement by the bolt 8a, the ends of the plate being flanged downwardly and slotted for the passage of link 8 of door C. Link 8 is normally locked to guide 8g by 20 means of a latch 8h of bell-crank shape pivoted on link 8 and urged by spring 8i into position to maintain the notched leg of lever 8h in engagement with the side edge of one flange of guide 8g so as to prevent link 8 from moving axially of 25 guide 8g. A stop 8j on link 8 limits the swinging movement of lever 8h, and the portion of lever 8h in advance of the notch is beveled as at 8k to permit ready engagement of the lever 8h with the guide when approaching the latter. Lever 8h 30 is swung out of engagement with guide 8g by means of a cord 8m extending from lever 8h and running substantially parallel with link 8 toward door C, said cord passing downwardly over a pulley 8n carried by the inner end of link 8, and extending to a latch on the door C. The latch (Fig. 15) comprises a latch lever 50 connected with the cord 8m and pivoted in a plate 51 (Fig. 17) inset flush with face of door C, the loop end of the lever 35 50 only projecting through the opening in the 40 door plate 51. A small spring 52 connects the top of latch lever 50 to the plate 51 to normally maintain the lever in inoperative position and returns the lever 50 to normal position when released. The free end of lever 50 may be padlocked (Fig. 45 15) to an eye 52 on plate 51. When not padlocked, in order to open the single entrance door C (with floor block C2 turned back) latch lever 50 is pulled out, drawing cord 8m down releasing the trip dog 8h from engagement with guide 8g 50 55 permitting door C to freely swing open. The dog 8h is designed to automatically "lock" when door C is returned to closed position.

I also provide electrical means, somewhat similar to that shown in my co-pending application Ser. No. 391,445, for power operating the unit, the same being illustrated in Figs. 1, 8, 9 and 10. The electrical means is bracketed in place under rafters or ceiling R in rear of and substantially 60 normal to the counterbalancing frame of the compound lever when the doors are in closed position; same preferably comprising a pair of side rails 10 carrying chain sprockets 11 and 12 journaled adjacent the ends of the rails. One sprocket such as 11 may be mounted in adjustable bearings 11a. The other sprocket may be driven by a motor controlled by a master switch. Around the sprockets 11, 12 runs a chain 13 and I provide plates 14 engaging the inner faces of the runs 65 of chain 13 respectively to prevent sagging thereof. One of the links of the chain 13 carries a lug 13a adapted to engage either the upper trip 15b or the lower trip 15a of a carriage 15 mounted to roll upon side rails 10 which form the track 70 75 75

on which carriage 15 is moved when lug 13a of the chain 30a engages the trips 15a or 15b.

Each trip 15a and 15b consists of a roller mounted on the end of a pivoted L-shaped arm 15d (Fig. 10) with a spring clip 15e mounted between the roller and the heel of the L but spaced from the roller. The other leg of the arm extends to the side of the carriage 15 into position to strike against an abutment 15f or 15g (Fig. 1). When making contact lug 13a forces past the spring clip 15e and lies between the clip 15e and roller 15a or 15b thereby positively controlling the movement of the carriage until the release is made at the end of travel of the carriage by side arms 15d striking against the tripping block 15f or 15g provided at the end of the carriage travel, thereby swinging the roller 15a or 15b to one side and allowing the lug 13a to pass.

Carriage 15 carries a fixed arm 15c connected by a relatively long link 16 to one arm of a bell crank 17 pivoted as at 17a adjacent the roller 7 on a clip 17b secured to the end of frame 6 of compound lever (see Fig. 3), the other arm of bell crank lever 17 carrying a traveler roller 17c operating against the underside of the ceiling R and disposed to roll in advance of roller 7 so that a push by link 16 will pivot bell crank 17 on its traveler wheel 17c which being held by the curved bracket 17d acts as a fulcrum for bell crank lever 17 to pull the rear end of frame 6 down so that a roller 7 may be readily rolled past the opening R' and the pull down of the frame lifts the door assembly at the opposite end of the frame 6 and when both the traveler 17c and roller wheel 7 have engaged the underside of ceiling R the door assembly will be maintained in raised position while being swung to "open" position.

A suitable trip-dog 18 is used to normally lock the bell crank lever 17 in raised position, said trip dog 18 being pivoted on bracket 17b and having one end extending beyond the bracket and its other end normally engaging a ratchet tooth 17e on the lever 17 and being held in such engagement by a spring 18a. In Fig. 3, the parts are shown in position ready to swing at the ceiling level the trip dog 18 holding the traveler wheel 17c and roller 7 in bearing relation to the ceiling R throughout the opening and closing movement of the doors until the doors are brought again into closed position, when the trip dog 18 is released by striking the abutment 19, and the pull of the electric carriage 15 through link 16 plus the weight of the door assembly drops the door assembly into lowered position.

A "lifting" element is provided within the opening R' of the ceiling and adapted to be engaged by the roller 7, when opposite said opening R'. The element consists of a bearing bar 20 lying in the plane of the lower face of ceiling R and having an offset extension 20a hinged as at 20b to the top of ceiling R, the outer end of bar 20 being flanged downwardly as at 20c tangent to the roller 7 when frame 6 is in fully "closed" position. Portion 20a extends between a pair of substantially vertically pivoted arms 21 carrying at their outer ends a hook rod 22 which is connected through spring 23 with a bracket 24, the end of spring 23 being adjustably connected with said bracket to vary the spring tension. Bars 25 also connected to the upper ends of arms 21 are hingedly connected as at 26 to the bearing bar 20 by means of a hinge plate 27 adjustably mounted on bar 20 above the approximate center of roller 7. Hinge plate 27 is adjustable "in" or "out" to increase or decrease the leverage of the

downward thrust. In the closing movement of the door assembly roller 7 rolls off the ceiling onto the bearing bar 20. As the bearing bar 20 is raised by weight of the door assembly, assisted by the manual or mechanical means, the spring tension remains about the same up to a certain point of the upward movement when it approaches a point where the spring tension would be overcome. A member 28 fixed on the portion 20c of bar 20 carries a small wheel or roller 28a at its upper end adapted to contact with hook rod 22 as the point of tension overcoming is reached so as to just hold the door assembly in closed down position. The opening of the door is by applying manual or mechanical lift at the door assembly or counterbalanced end of the lever 6 just sufficient to break the "hold" at the lifting element.

Above the path of travel of carriage 15 is a bar 29 upon which is mounted a three way switch 30 having its trigger engaged with a slide bar 31 mounted in bearings parallel with the side frames 10. Bar 31 is provided with stops 31a and 31b mounted adjacent the ends thereof adapted to engage trips 15x carried by the carriage 15. When carriage 15 has drawn the doors A, B, C, into "open" position and is at the end of its specified travel, trip 15x engages the stop 31a on reversing rod 31. The spring tension of trip 31a is sufficient to slide the rod 31 to shift the contacts of switch 30. Adjustment of the stops 31a and 31b on reversing rod 31 will give the desired length of travel for carriage 15.

In operation, upon throwing the switch for "opening" movement the motor will set chain 13 in motion and lug 13a will engage pawl roller 15b and move the carriage 15 which is connected by linkage to the frame 6 of the compound lever, and thus draw the counterbalanced door assembly "open". As carriage 15 nears end of its opening travel trip 15x on the carriage engages stop 31a of bar 31 and shifts the contacts of switch 30. To close the doors, turn switch 30 to "closing" contact and the carriage 15 is drawn to "closed" end of travel by lug 13a engaging roller 15a, the stop 31b shifting the switch contacts at the end of the carriage travel and stopping the motor. The belt 13 runs in the same direction for both movements, but the direction of motion of carriage 15 is governed by the engagement of lug 13a with rollers 15a or 15b.

Referring to Fig. 4, handles 32 are provided on the door B, inside and out, for raising and lowering the door assembly by manual control. Also an electric Yale lock 33 is provided adapted to break the current through the motor when the same is locked, the connections being arranged so that the motor cannot be started until the lock bolt is withdrawn from the notch in the locking bar 34 by means of a key inserted from the outside or by turning a knob on the inside of the door B. Bar 34 is secured to lower end of bracket 3 or may be a continuation of hinge bar 3c as shown in Fig. 7. The vertical movement of the door assembly on the carriage 2a permits the bar 34 to move in its keepers 34a as the doors are raised and lowered, and when doors are lowered the bolt of the Yale lock may enter the notch and hold the doors locked against movement in any direction.

I do not limit my invention to the exact form shown in the drawing for obvious changes may be made therein within the scope of the claims.

I claim:-

1. In combination, a swinging door having a

- plurality of hinged sections; a pivoted swingable carrier for said door connected to one section and adapted to move the door from fully closed position into fully opened position; a member 5 movably mounted on the carrier; and means operated by the member for yieldably aligning the several sections edgewise as they move into fully closed or into fully opened positions.
2. In a combination as set forth in claim 1, 10 said means comprising toggle members connecting the end door sections, and a yieldable member tending to flatten the toggle.
3. In a combination as set forth in claim 1, 15 said means comprising a toggle connecting the end door sections; a yieldable member tending to flatten the toggle; and spring pressed guides adjacent the extreme limits of movement of the door coating with their respective end door sections.
- 20 4. In combination, a swinging door having a plurality of hinged sections; a swingable carrier for said door adapted to move same from fully closed position into fully opened position; yieldable guides adjacent the extreme limits of movement of the door; and means operated by said 25 guides aligning the sections edgewise as the door nears its fully closed or fully opened position.
5. In a combination as set forth in claim 4, a 30 base unit carrying the carrier and guides and comprising a track for the carrier shaped to conform with the swing of the carrier; curved portions forming the guides for the said means extending from the ends of the track; a center bearing plate for the carrier; frame members 35 connecting the track and curved portions with the bearing plate; and means yieldably connecting the outer ends of the curved portions to the frame members.
6. In a combination as set forth in claim 4, a 40 base unit carrying the carrier and guides and comprising an arcuate channel for the carrier having its center of curvature concentric with the pivot of swing of the carrier; reverse curved portions forming the said guides for the said means extending from the ends of the channel; a center bearing plate for the carrier; frame members 45 connecting the channel and reverse curved portions with the bearing plate; and means yieldably connecting the outer ends of the reverse curved portions to the frame members.
7. In combination, a swinging door having a 50 plurality of hinged sections; a swingable carrier for said door connected to the middle section and adapted to move the same from fully closed position into fully opened position; toggle links connecting the side door sections for imparting the movement of one section to the other; yieldable guides adjacent the extreme limits of movement 55 of the door; and devices on the side door sections engaging said guides for aligning the sections edgewise as the door approaches fully closed or fully opened positions.
8. In a combination as set forth in claim 7, 60 means for permitting one side door section to be opened independently of the other.
9. In a combination as set forth in claim 7, the 65 guide engaging device of one side door section being mounted on a frame pivotally supported upon the middle door section, said frame being connected with its respective toggle link; and latch means for locking said side door section to the frame whereby when the latch is sprung said section may be opened without operating the 70 toggle.
10. In a combination as set forth in claim 7, a spring normally urging separation of the toggle links.
11. In combination, a swinging door having a 75 plurality of hinged sections; a pivoted swingable carrier pivotally connected to one section and adapted to move said door from its fully closed position into its fully opened position; a member movably mounted on the carrier; and means operated by the member for aligning the sections 10 edgewise as they move into fully closed or into fully opened positions and for flexing the hinged sections to substantially conform with the swing of the carrier while moving from one position to the other.
12. In a combination as set forth in claim 11, 15 said means comprising means for causing the hinging movement of one side door to swing the other, means for causing one end door to initially flex the hinged sections at the beginning of the 20 opening or closing movement, and means for causing the other end door to re-align the sections at the end of the said movement.
13. In a combination as set forth in claim 11, 25 said carrier moving in a horizontal plane; and said door sections being vertically adjustable with respect to the carrier; and means for raising and lowering the door sections as the carrier is swung.
14. In a combination as set forth in claim 11; 30 said carrier moving in a horizontal plane; and said door sections being horizontally and vertically adjustable with respect to the carrier.
15. In a combination as set forth in claim 11, 35 a bracket radially adjustable on the carrier; a hinge rod for said door carried by said bracket; said door section being axially movably mounted on said rod; and means for moving said door section on the rod.
16. In a combination as set forth in claim 11, 40 said carrier swinging in a horizontal plane; a bracket radially adjustable on the carrier; a vertically disposed hinge rod for said door carried by said bracket; said door section being vertically movably mounted on said rod; and a counterbalancing lever connected with said door and 45 pivoted on the carrier.
17. In combination, a swinging door; a horizontally swingable carrier for swinging the door from fully closed to fully open positions; a lever having one end connected with the door and pivoted on the carrier; a roller at the other end of the lever engaging a cam surface for holding the door in elevated position except when the door is in fully closed position; and a yieldable section in the cam surface engaged by the roller when 50 the door is fully closed for substantially counterbalancing the weight of the door.
18. In a combination as set forth in claim 17, 55 said yieldable member comprising a hinged bearing bar adapted to swing upwardly; adjustable means for yieldably maintaining the bar in normal position; and means for limiting the hinging movement of the bar.
19. In a combination as set forth in claim 17, 60 a power driven carriage; a link connecting the carriage to the roller end of the lever for swinging the lever in both directions; means interposed between the link and lever for maintaining the door in elevated position when entering upon the yieldable section; and a trip for releasing said 65 means.
20. In a combination as set forth in claim 17, 70 a power driven carriage; a link connecting the carriage to the roller end of the lever for swinging the lever in both directions and a bell crank 75

- operated by the link, a traveler carried by the bell crank engaging the cam surface in advance of the roller; a spring pressed pawl normally holding the bell crank in position to normally maintain the door in elevated position when entering upon the yieldable section; and a trip for releasing the pawl when the door is in fully closed position.
- 5 21. In combination, a swinging door having a plurality of hinged sections, a swingable carrier for the door connected to the middle section and adapted to move same from fully closed to fully open position, a toggle member movably mounted in the carrier; toggle links respectively connecting the side door sections to the member for im- 10 parting the movement of one side section to the other; and means for releasing one link connection for permitting its related side door section to be opened independently of the other.
22. In combination, a swinging door having a 15 plurality of hinged sections, a swingable carrier for the door connected to the middle section and adapted to move same from fully closed to fully open position, a toggle member movably mounted in the carrier; toggle links respectively connect- 20 ing the side door sections to the member for im- parting the movement of one side section to the other; a guide on said member slidably receiving one link; means for normally locking the link in said guide; and means for releasing the link for 25 permitting its related side door section to be opened independently of the other.
- 30
23. In combination, a swinging door having a plurality of hinged sections, a swingable carrier for the door connected to the middle section and adapted to move same from fully closed to fully open position, a toggle member movably mounted 5 in the carrier; toggle links respectively connecting the side door sections to the member for im- parting the movement of one side section to the other; a guide on said member slidably receiving the end of one link; a trip dog normally locking the link in said guide; and manual means for releasing the dog for permitting its related side door section to be opened independently of the other.
24. In combination, a swinging door having a 15 plurality of hinged sections, a swingable carrier for the door connected to the middle section and adapted to move same from fully closed to fully open position, a toggle member movably mounted in the carrier; toggle links respectively connect- 20 ing the side door sections to the member for im- parting the movement of one side section to the other; a guide block on said member slidably receiving the end of one link; a trip dog on the said link normally locking the link to the block; a 25 latch lever on the related door; and a flexible member connecting the latch lever and dog whereby when the latch lever is actuated the related side door section may be opened independently of the other.

30. ERNEST L. SHAFFER.
